UNITED STATES PATENT OFFICE.

FRANK A. KUNTZ, OF NEW YORK, N. Y.

TEMPERATURE-REGULATOR.

1,104,680.

Specification of Letters Patent.

Patented July 21, 1914.

Application filed January 27, 1913. Serial No. 744,375.

To all whom it may concern:

Be it known that I, FRANK A. KUNTZ, a citizen of the United States, and resident of the city of New York, in the county of 5 Queens and State of New York, have invented certain new and useful Improvements in Temperature-Regulators, of which the following is a specification.

This invention relates to means for maintaining the temperature of fluids at a uniform degree, and particularly for maintaining a uniform temperature in apartments, dwellings, public halls, etc.

The principal object of my invention is 15 to provide simple, effective, reliable, and improved means for this purpose.

In carrying out the invention, a friction wheel is provided which is continuously rotated from the drive shaft of a blower that 20 feeds air into the apartment through a hot and a cold duct. Friction-disks slidable in the direction of their axes are actuated by a solenoid in a circuit provided with a thermostat located in the apartment, whereby 25 one or the other of said disks is caused to engage with said wheel, and to be rotated thereby, by the making and breaking of said circuit. Said disks are mounted on a frame which is shiftable toward and away 30 from said friction wheel, and a valve for closing and opening either of said ducts is connected to said frame. A screw carried with said frame is geared to said disks and engages with a fixed tapped portion, whereby 35 by said frame is shifted in one direction or reversed in an opposite direction and said frame set to close or open either of said ducts, according to whichever disk is in engagement with said wheel. Means are provided to disengage said disks from said 40 wheel to stop the operation of said mechanism when said valve is set. The disk axes approach said wheel while it is in engagement with one of said disks and recede 45 therefrom while in engagement with the other of said disks, so that said valve when set in one position is swung at an accelerating rate and when set to the other position is swung at a retarding rate, whereby quick 50 commencement of admission of warm air and slow commencement of admission of cold air is effected.

Other objects and advantages will herein-after appear.

55 In the accompanying drawings,—Figure 1

is a general elevation of the valve operating mechanism. Fig. 2 is a general diagram of the electric circuit of the temperature regulator. Fig. 3 is a side view of Fig. 1. Fig. 4 is a diagram showing the hot 60 and cold ducts, the arrangement of the blower, and the valve for the ducts in an apartment heating system, with which my invention is shown as adapted.

A duct 1, Fig. 4, conducts the air from 65 the exterior of the apartment to the casing 2^a, where a blower 2 is located, and said blower sends the air into a cold duct 3 or a hot duct 4, depending upon which of said ducts is open, and into the duct 5 in the direction of the arrows, from where the air is directed into the apartment, the temperature of which it is desired to maintain at a uniform degree.

Upon the drive shaft 6, Figs. 1 and 4, of 70 the blower 2 is mounted a worm 7, which drives the valve operating mechanism shown in Fig. 1, said mechanism being suitably supported in place. Said worm meshes with its wheel 8 keyed on a shaft 9 which 75 rotates in a bearing 10 forming part of an upright support 11 extending from a horizontal base 12, and a friction wheel 13 is fixed on shaft 9 whereby it is continuously 80 rotated by the operation of said blower. 85 A frame 14 is provided with guide-channels 15 fitting on tracks 16, forming part of the base 12, which extend in the direction of the axis of friction-wheel 13, whereby the frame is slidable toward and away therefrom.

Friction disks 17, 18, adaptable to be driven by the wheel 13, are secured upon or form part of a hollow shaft or sleeve 19 which is mounted rotatably in a bearing 95 20 on frame 14 and is slidable longitudinally therein, the axis of sleeve 19 being perpendicular to the axis of the wheel 13. A pinion 21 secured upon sleeve 19 and driven therewith meshes with a gear 22 secured 100 upon a rotatable intermediate shaft 23 running in bearings 24, 25 of frame 14, and a worm 26 fixed on shaft 23 meshes with a wheel 27 keyed upon a shaft 28, which is thereby rotated in its bearing 29 forming 105 part of the frame 14. Said shaft carries a screw 30, preferably square-threaded, which engages with a co-operating tapped portion 31 of a hub 32 forming part of the fixed support 11, so that said screw threads inwardly 110

or outwardly and the frame with the mechanism carried thereupon are consequently shifted toward or away from the friction-wheel 13, depending upon the direction of 5 rotation of said screw, which in turn depends upon the direction of operation of the mechanism carried by the frame. To the frame 14 is pivoted a link 33 at 33^a, connected by a link 33^b to a valve 34, hinged at 10 34^a, Fig. 4, which is thus actuated by the movement of the frame to open and close the ducts 3 and 4.

In the apartment, the temperature of which it is desired to maintain uniform, is 15 located a suitable thermostat 35, Fig. 2, in a circuit preferably branched from main wires 36, 37 that supply current to a motor 38 which drives the blower 2. A solenoid 39 in said circuit is secured to the frame 14 and the core 40 thereof passing through the frame at 14^a has a portion 41 of a reduced diameter which extends within the sleeve 19, the shoulder 42 and a screw 43 threading into the end of said core maintaining said 25 sleeve in place longitudinally. Said core is normally pressed upon by a spring 44, fixed to the solenoid, which bears against pins 45 and forces the core and its depending parts outward.

30 If the temperature of the apartment falls below a degree which it is desired to maintain, the thermostat 35 closes the circuit as shown, and conducts the current from wire 36 along wire 46, through the resistance 47 which reduces the current, along wire 48, the thermostat, wires 49, 50, and through the solenoid 39, which is thereby energized. The solenoid-core 40 is therefore drawn in and the disk 18 thus caused to bear against 40 the friction-wheel 13, which being driven continually rotates said disk and operates the mechanism whereby the frame 14 is shifted away from said wheel, and the valve 34 is thereby set to the position shown in 45 Fig. 4. The air is thereupon directed by the blower 2 into the duct 4, which having a source of heat 51 feeds warm air to the apartment, and raising the temperature therein restores it to the desired degree.

50 When the temperature of the apartment rises above a certain desired degree, the thermostat 35 breaks the circuit, as indicated by the dot and dash lines, and the solenoid 39 is deenergized. In this case, the 55 spring 44 causes the disk 17 to bear against the friction wheel 13 and to be rotated thereby, so that the mechanism is reversed, the frame 14 shifted toward said wheel, and the valve 34 thus swung and set to its opposite position, shown by the dot and dash lines. The hot duct 4 being thus closed, the 60 cold air is directed by the blower 2 into the apartment through the duct 3, and lowering the temperature therein restores it to the desired degree.

The high speed from the blower shaft 6 is greatly reduced through the mechanism, by the worm 7 and wheel 8, friction wheel 13 and disk 17 or 18, pinion 21 and gear 22, worm 26 and wheel 27, and the screw 30, so 70 that the valve 34 is gradually swung when set to its aforesaid positions; it being deemed better to effect the change gradually from the admission of hot to cold air and vice versa. The rate of swinging of 75 said valve may be altered, if desired, by changing the gears 21 and 22.

It will be noted that when the disk 17 engages with the wheel 13 to admit cold air to the apartment, the sleeve 19, being carried by the frame 14, advances toward said wheel, while when the disk 18 engages with said wheel to admit warm air said sleeve recedes from said wheel. This causes the mechanism to operate at an accelerating rate 85 when the disk 17 is in engagement with wheel 13 to swing the valve 34 to admit cold air, due to the continual decrease of the relative diameter of said disk, and to operate at a retarding rate when the disk 18 is in engagement to swing said valve to admit warm air. The valve 34 is thereby swung very slowly at the commencement of opening of duct 3 for feeding cold air, and is 90 swung rapidly at the commencement of opening of duct 4 for feeding warm air. This action is advantageous, inasmuch as it is desired to commence quickly the admission of warm air into the apartment when it is required, and to commence the admission 100 of cold air more slowly for restoring the uniform temperature.

When the frame 14 reaches the end of its stroke in either direction and sets the valve 34 to either of its aforesaid positions, the 105 operation of the mechanism is stopped by the disengagement of the engaging disk from the friction wheel 13. In the case of disk 17, the edge 52 thereof strikes against a beveled cam-piece 53, secured to support 110 11 at 53^a, which bears against the disk contrary to the pressure of spring 44, and thus disengages it from the wheel 13. When the frame 14 reaches the opposite end of its stroke, shown in Fig. 1, an arm 54, secured 115 to the support 11 at 55 and having a bent end 56, strikes the end 57 of a lever 58 fulcrumed at 59 upon a bracket 60 extending from frame 14, and forces the opposite end 61 of the lever to bear against the disk 18 120 contrary to the pull of the solenoid, whereby it is disengaged from the wheel 13 and the mechanism stopped. A spring 62 fixed to the bracket 60 presses against the end 61 of said lever to normally maintain it away 125 from the disk 18.

Suitable material may be selected for the construction of the various parts of the mechanism.

It will be evident from the foregoing that 130

although my invention has been shown here as adapted for regulation of uniform temperature of apartments provided with a source of heat in wintertime, it may be also similarly used with cooling means in summertime. The invention may be also used in connection with the regulation of the temperature of air chambers or of any fluid which it is desired to maintain at a uniform degree, in the various arts or manufacturing processes.

Variations may be resorted to within the scope of the invention, and portions of the improvements may be used without others.

Having thus described my invention, I claim:

1. The combination with a valve for admitting and shutting off fluid for maintaining uniform temperature, of a circuit having thermostatic means to make and break the circuit, and mechanism being operated by means in said circuit to set said valve in one position when said circuit is broken and to reverse itself when said circuit is closed to set said valve in its opposite position, said mechanism being adaptable to be driven at an accelerating rate when said valve is being set to one position and at a retarding rate when being set to its opposite position.

2. The combination with a valve for admitting and shutting off fluid for maintaining uniform temperature, of a circuit having thermostatic means to make and break the circuit, a continuously driven shaft in the same direction at a uniform speed, and mechanism driven thereby being operated by means in said circuit to set said valve in one position when said circuit is broken and to reverse itself when said circuit is closed to set said valve in its opposite position, said mechanism having means to set said valve at an accelerating rate to one position and at a retarding rate to its opposite position.

3. The combination with a valve for gradually admitting and shutting off hot and cold air, of a circuit having thermostatic means to make and break the circuit, and mechanism being operated by means in said circuit to set said valve in one position when the circuit is broken and to reverse itself when said circuit is closed to set said valve in its opposite position, said mechanism adaptable to set said valve at a retarding rate when admitting hot air and at an accelerating rate when admitting cold air.

4. The combination with a valve for admitting and shutting off fluid for maintaining uniform temperature, of a circuit having thermostatic means to make and break the circuit, a shaft driven continuously in the same direction, and mechanism driven thereby by means in said circuit to set said valve in one position when said circuit is broken and to reverse itself when said circuit is closed to set said valve in its opposite posi-

tion; said mechanism including a continuously driven friction wheel, and a pair of friction-disks being actuated by said operating means to engage one or the other of said disks with said wheel to operate the mechanism in opposite directions.

5. The combination with a valve for admitting and shutting off fluid for maintaining uniform temperature, of a circuit having thermostatic means to make and break the circuit, a shaft driven continuously in the same direction, and mechanism driven thereby being operated by means in said circuit to set said valve in one position when the circuit is broken and to reverse itself when said circuit is closed to set said valve in its opposite position; said mechanism including a shiftable frame, said valve connected to said frame, and means actuated by said operating means to shift said frame in opposite directions to open and close said valve.

6. The combination with a valve for admitting and shutting off fluid for maintaining uniform temperature, of a circuit having thermostatic means to make and break the circuit, a shaft driven continuously in the same direction, and mechanism driven thereby being operated by means in said circuit to set said valve in one position when said circuit is broken and to reverse itself when said circuit is closed to set said valve in its opposite position; said mechanism including a continuously driven wheel, and wheels shiftable toward and away from said wheel being actuated by said operating means to engage and disengage one or the other thereof with said former wheel to operate the mechanism in opposite directions.

7. The combination with a valve for admitting and shutting off fluid for maintaining uniform temperature, of mechanism including a continuously driven wheel, a shiftable frame, said valve connected thereto, shiftable wheels on said frame adaptable to engage one or the other thereof with said other wheel, an actuating shaft for said frame geared to said shiftable wheels for shifting said frame to actuate said valve, and means to set one or the other of said shiftable wheels into engagement with said former wheel for operating the mechanism in opposite directions to open or close said valve.

8. The combination with a hot and cold duct, and a valve for shutting and opening said hot and cold duct, of a circuit having thermostatic means to make and break the circuit, a motor running continuously in the same direction, mechanism driven thereby for operating said valve, a magnetizing coil energized by said circuit driving said mechanism in one direction to operate it to set said valve in one position, and a spring ac-

tuating said mechanism to be driven in an opposite direction to set said valve in its opposite position.

9. The combination with a valve for admitting and shutting off fluid for maintaining uniform temperature, a circuit, and means to make and break said circuit, of a continuously driven shaft in the same direction, and mechanism driven thereby setting said valve in one position when said circuit is broken and reversing itself when said circuit is closed to set said valve in its opposite position; said mechanism including a continuously driven friction-wheel, a pair of friction-disks actuated by the making and breaking of said circuit to engage one or the other of said disks with said wheel to operate the mechanism in opposite directions, and means to disengage said disks from said wheel for stopping the operation of said mechanism when said valve has been set to either of its positions.

10. The combination with a valve for admitting and shutting off fluid for maintaining uniform temperature, a circuit, and means to make and break said circuit, of a continuously driven shaft in the same direction, and mechanism driven thereby setting said valve in one position when said circuit is broken and reversing itself when said circuit is closed to set said valve in its opposite position; said mechanism including a continuously driven friction wheel, and a pair of spring-pressed friction-disks actuated to engage one of its disks with said wheel to operate the mechanism in one direction when the circuit is broken and to engage the other disk to reverse said direction of operation when the circuit is closed.

40 11. The combination with a valve for admitting and shutting off fluid for maintaining uniform temperature, a circuit, and means to make and break said circuit, of a continuously driven shaft in the same direction, and mechanism driven thereby setting said valve in one position when said circuit is broken and reversing itself when said circuit is closed to set said valve in its opposite position; said mechanism including a continuously driven friction wheel, a pair of spring-pressed friction-disks actuated to engage one of its disks with said wheel to operate the mechanism in one direction when the circuit is broken and to engage the other disk to reverse said direction of operation when the circuit is closed, a beveled cam to press against one of said disks to disengage it from said wheel for stopping said mechanism when said valve is set, and a lever to press against said other disk to similarly disengage it.

12. The combination with a valve for admitting and shutting off fluid, of a circuit having thermostatic means to make and break the circuit, a motor running continu-

ously in the same direction, mechanism driven thereby for operating said valve, a magnetizing coil energized by said circuit operating said mechanism to set said valve in one position, a spring reversing said mechanism to set said valve in its opposite position, and means for making the pull of said energized coil and spring ineffective to stop the operation of said mechanism when said valve has been set to either of its positions.

13. The combination with a valve for admitting and shutting off fluid for maintaining uniform temperature, a circuit, and means to make and break said circuit, of a continuously driven shaft in the same direction, and mechanism driven thereby setting said valve in one position when said circuit is broken and reversing itself when said circuit is closed to set said valve in its opposite position; said mechanism including a shiftable frame, said valve connected to said frame, means actuated by the making and breaking of said circuit to shift said frame in opposite directions to open and close said valve, and means for stopping the movement of said frame when said valve has been set to either of its positions.

14. The combination with a valve for admitting and shutting off fluid for maintaining uniform temperature, a circuit, and means to make and break said circuit, of a continuously driven shaft in the same direction, and mechanism driven thereby setting said valve in one position when said circuit is broken and reversing itself when said circuit is closed to set said valve in its opposite position, said mechanism including a shiftable frame, said valve connected to said frame, a tapped portion and a screw cooperating therewith for shifting said frame, and means actuated by the making and breaking of said circuit to cause said screw and tapped portion to engage for shifting said frame in opposite directions to open and close said valve.

15. The combination with a valve for admitting and shutting off fluid for maintaining uniform temperature, a circuit, and means to make and break said circuit, of mechanism having a drive shaft running continuously in one direction, a friction wheel driven continuously thereby, a frame shiftable toward and away from said wheel, said valve connected thereto, friction-disks on said frame shiftable in direction of their axes, an intermediate shaft on said frame geared to said disks, an actuating shaft for said frame driven by said intermediate shaft, and a tapped portion and screw being engaged by said actuating shaft to shift said frame in opposite directions to actuate said valve; said disks being set by the making and breaking of said circuit to engage one or the other thereof with said wheel for

operating the mechanism in opposite directions to open or close said valve.

16. The combination with a valve for admitting and shutting off fluid for maintaining uniform temperature, a circuit, and means to make and break said circuit, of mechanism having a continuously driven friction wheel, a frame shiftable toward and away from said wheel, said valve connected thereto, friction disks on said frame shiftable in direction of their axes, an actuating shaft on said frame geared to said disks, and a tapped portion and screw being engaged by said actuating shaft to shift said frame in opposite directions to actuate said valve; said disks being set by the making and breaking of said circuit to engage one or the other thereof with said wheel for operating the mechanism in opposite directions to open and close said valve.

17. The combination with a valve for admitting and shutting off fluid for maintaining uniform temperature, a circuit, and means to make and break said circuit, of mechanism having a continuously driven wheel, a shiftable frame, said valve connected thereto, shiftable wheels on said frame to engage with said former wheel, an actuating shaft on said frame geared to said shiftable wheels, and a tapped portion and screw being engaged by rotation of said actuating shaft to shift said frame to actuate said valve; said shiftable wheels being set by the making and breaking of said circuit to engage one or the other thereof with said former wheel for operating the mechanism in opposite directions to open and close said valve.

18. The combination with a valve for admitting and shutting off fluid for maintaining uniform temperature, a circuit, and means to make and break said circuit, of mechanism having a continuously driven wheel, a shiftable frame, said valve connected thereto, shiftable wheels on said frame to engage with said former wheel, an actuating shaft on said frame geared to said shiftable wheels, and a tapped portion and screw being engaged by rotation of said actuating shaft to shift said frame to actuate said valve; said shiftable wheels being set by the making and breaking of said circuit to engage one or the other thereof with said former wheel for operating the mechanism in opposite directions to open and close said valve, and means to disengage said shiftable wheels from said former wheel for stopping the operation of the mechanism when said valve is set.

19. The combination with a valve for admitting and shutting off fluid, of a circuit having thermostatic means to make and break the circuit, a motor running continuously in the same direction, mechanism driven thereby for operating said valve, a

magnetizing coil energized by said circuit operating said mechanism to set said valve in one position, and means to stop the operation of said mechanism when said valve is set by said coil while it continues to be energized.

20. The combination with a hot and cold duct, and a valve for shutting and opening said hot or cold duct, of a circuit having thermostatic means to make and break the circuit, a motor running continuously in the same direction, mechanism driven thereby being operated by means in said circuit to be driven in one direction to set said valve in one position when the circuit is closed, and a spring in said mechanism actuating it when the circuit is broken to be driven in an opposite direction to set said valve in its opposite position.

21. A temperature regulator having the combination with a circuit, a thermostat to make and break the circuit, a solenoid, a hot duct, a cold duct, and a valve for said ducts, of mechanism to operate said valve including a continually driven shaft, a friction wheel, a worm and wheel driven by said shaft driving said friction wheel, a frame shiftable toward and away from said friction wheel, friction disks on said frame mounted to shift in direction of their axes, an intermediate shaft on said frame geared to said friction disks, an actuating shaft for said frame, a worm and wheel driven by said intermediate shaft driving said actuating shaft, a tapped portion and screw being engaged by rotation of said actuating shaft to shift said frame in opposite directions, said valve connected to said frame, said solenoid fixed to said frame having its core connected to said disks, a spring pressing when said circuit is broken to engage one of said disks with said friction wheel to operate said mechanism to set said valve in one position, and said solenoid when energized by said thermostat closing its circuit engaging the other of said disks with said wheel to reverse the mechanism and to set said valve oppositely; of a beveled cam-piece striking said pressed disk to disengage it from said friction wheel and stop the mechanism when said valve is set, a lever pivoted on said frame, and a fixed arm striking said lever and pressing it against the other of said disks to disengage it from said friction wheel and stop the mechanism when said valve is set oppositely.

22. A temperature regulator having the combination with a circuit, a thermostat to make and break said circuit, a solenoid, a hot duct, a cold duct, and a valve for said ducts, of mechanism to operate said valve including a continually driven shaft, a friction wheel, a worm and wheel driven by said shaft driving said friction wheel, friction disks on said frame mounted to shift in di-

- rection of their axes, an intermediate shaft on said frame geared to said friction-disks, an actuating shaft for said frame, a worm and wheel driven by said intermediate shaft 5 driving said actuating shaft, a tapped portion and screw being engaged by said actuating shaft to shift said frame in opposite directions, said valve connected to said frame, a spring pressing when said circuit 10 is broken to engage one of said disks with said friction wheel to operate said mechanism to set said valve in one position, said solenoid when energized by said thermostat closing its circuit engaging the other of said 15 disks with said wheel to reverse the mechanism and to set said valve oppositely, and means to disengage said disks from said wheel for stopping the operation of said mechanism when said valve is set.
- 20 23. The combination with a valve for admitting and shutting off fluid, of a circuit having thermostatic means to make and break the circuit, a shaft driven continuously in the same direction, mechanism 25 driven thereby being operated by means in said circuit to set said valve in one position when said circuit is closed, means reversing said mechanism when said circuit is broken to set said valve in its opposite position, and

means for stopping the operation of said 30 mechanism when said valve is set by the closing of said circuit while said circuit continues to be closed.

24. The combination with a valve for admitting and shutting off fluid for maintaining uniform temperature, of mechanism including a continuously driven wheel, a shiftable frame, said valve connected thereto, shiftable wheels on said frame to engage with said other wheel, an actuating shaft for 35 said frame geared to said shiftable wheels for shifting said frame to actuate said valve, means to set said shiftable wheels to engage one or the other thereof with said former wheel for operating the mechanism in opposite directions to open or close said valve, and means to disengage said shiftable wheels from said former wheel for stopping the operation of the mechanism when said valve is 40 set.

Signed at the city of New York, in the county of New York, and State of New York, this 25th day of January, A. D. 1913.
